SHADING GENERATOR

Robert E. Kessler, Upper Montclair, N. J., assignor to Allen B. Du Mont Laboratories, Inc., Passaic, N. J., a corporation of Delaware

Application January 13, 1942, Serial No. 426,566

10 Claims. (Cl. 178—7.2)

This invention relates to the generation and phasing of a high frequency sine wave. It is particularly useful for shading a television picture.

By this invention a sine wave can be obtained and varied over a wide range of line scanning frequencies, without complicated circuit adjustments, for the purpose of shading television pictures in which widely different scanning frequencies are used. This is accomplished without the necessity of supplying a special or separate synchronizing pulse to the shading generator. A sawtooth impulse is used for the input for generating the sine wave and the phase may be changed over the extraordinary wide range of 360 degrees.

One of the objects of this invention is to obtain a sine wave that can be used for shading a television picture over a wide range of scanning frequencies where a flexible scanning system is employed. In carrying out the invention a sawtooth signal at the horizontal scanning rate and a sawtooth signal at the vertical scanning rate are converted into sine waves and these sine waves are used for shading an iconoscope. When the scanning rate is changed by changing the frequency of the sawtooth signal, the frequency of the sine wave follows automatically over a wide range of frequencies.

The invention may be understood from the description in connection with the accompanying drawing, in which:

Fig. 1 is a block diagram showing an arrangement of parts; and

Fig. 2 is a circuit arrangement for generating and shifting the phase of the sine wave used for shading.

As indicated in Fig. 1, a vertical synchronizing sawtooth signal is fed to the mixer tube 1 indicated diagrammatically; a 60-cycle sine wave from a power line is fed to the mixer tube 2; the same vertical synchronizing sawtooth signal is fed to the parabola generator 3, the output of which is fed to the mixer 4; a horizontal synchronizing sawtooth signal is fed to the mixer 5; the same horizontal synchronizing sawtooth signal is fed to the parabola generator 6, the output of which is fed to the mixer 7; and the same horizontal synchronizing sawtooth signal is fed to the sine-wave generator 8, the output of which is fed to the mixer 9. The composite signals are led to the output tube 10 and thence to an iconoscope for shading the same.

Fig. 2 shows how the horizontal synchronizing sine wave is generated and phased, from which it

will be obvious how the vertical synchronizing wave is also generated and phased in a similar manner.

In Fig. 2 the horizontal synchronizing signal is applied across the resistor R_1 to the grid G of the vacuum tube V , the resistor R being adjusted to supply the proper bias on this grid. The condenser C_1 and inductance L_1 , shunted by the resistor R_2 , are adjusted to resonate the plate P of the tube V so as to oscillate at the frequency of the signal applied to the grid G . The resulting sine waves are caused to appear through the condenser C_2 across the primary T_1 of the transformer. The secondary T_2 of this transformer is grounded as indicated, and is loaded with a series circuit containing the condenser C_3 and variable resistor R_3 . By varying the resistance R_3 the sine wave from the secondary T_2 can be shifted over a phase angle of approximately 180° . The reversing switch S between the transformer secondary T_2 and the load enables the phase angle to be shifted 180° so that the sine wave can then be shifted along the other 180° of the 360 degrees. The Q is made low so that broad tuning, say over an octave, is possible.

Scanning frequencies can be obtained with this invention from 15,750 cycles per second for 525 line, 30 frame television pictures to 9,375 cycles per second for 625 line, 15 frame television pictures, for shading without any change in tuning or any other circuit adjustments being necessary.

This invention is also useful for observing a television signal at line frequency on an oscilloscope. While doing this the sine-wave is used as a time base. When it is desired to observe a remote television signal on an oscilloscope, the horizontal synchronizing frequency sawtooth signal of the television receiver is applied to the oscillator input to produce a sine wave for use in the oscilloscope. The tube V of Fig. 2 and its circuits constitute an oscillator for this purpose.

While the description above has set forth the details for converting a sawtooth wave over a range of horizontal scanning frequencies into a sine wave of variable phase suitable for television shading purposes, it has been found that input signals of impulse shape and other wave forms at horizontal scanning frequency can also be applied to the circuit of Fig. 2 resulting in variable phase sine waves suitable for shading and suitable for oscilloscope sweep circuits.

What is claimed is:

1. In a device for generating and phasing sine waves from sawtooth signals for shading television pictures, a vacuum tube with a biased grid

to which the sawtooth signal is applied, a resonant circuit connected to the plate of said tube to cause oscillations at the frequency of the sawtooth signal, a transformer to the primary of which said oscillations are applied, and a series circuit load on the secondary of said transformer.

2. In a device for generating and phasing sine waves from sawtooth signals for shading television pictures, a vacuum tube with a biased grid to which the sawtooth signal is applied, a resonant circuit connected to the plate of said tube to cause oscillations at the frequency of the sawtooth signal, a transformer to the primary of which said oscillations are applied, a series circuit load on the secondary of said transformer, and a variable resistance in said last named circuit.

3. In a device for generating and phasing sine waves from sawtooth signals for shading television pictures, a vacuum tube with a biased grid to which the sawtooth signal is applied, a resonant circuit connected to the plate of said tube to cause oscillations at the frequency of the sawtooth signal, a transformer to the primary of which said oscillations are applied, a series circuit load on the secondary of said transformer, and a reversing switch in said last named circuit.

4. In a device for generating and phasing sine waves from sawtooth signals for shading television pictures, a vacuum tube with a biased grid to which the sawtooth signal is applied, a resonant circuit connected to the plate of said tube to cause oscillations at the frequency of the sawtooth signal, a transformer to the primary of which said oscillations are applied, a series circuit load on the secondary of said transformer, and a gain control connected to the output of said last named circuit.

5. In a device for generating and phasing sine waves from sawtooth signals for shading television pictures, a vacuum tube with a biased grid to which the sawtooth signal is applied, a resonant circuit having a low Q connected to the plate of said tube to cause oscillations at the frequency of the sawtooth signal, a transformer to the primary of which said oscillations are applied, and a series circuit load on the secondary of said transformer.

frequency of the sawtooth signal, a transformer to the primary of which said oscillations are applied, and a series circuit load on the secondary of said transformer.

6. In a device of the character described, means for producing from a line frequency sawtooth signal a composite signal for line frequency shading of television pictures, said means comprising a sine wave generator and a parabola generator to which said sawtooth signal is applied, and mixers for mixing the outputs therefrom for application to an iconoscope for shading purposes.

7. In a device of the character described, means for producing from a line frequency sawtooth signal a composite signal for line frequency shading of television pictures, said means comprising a sine wave generator and a parabola generator to which said sawtooth signal is applied, and mixers for mixing the outputs therefrom and said sawtooth signal for application to an iconoscope for shading purposes.

8. The device of claim 6, in which said sine wave generator is adapted to have its phase shifted over approximately 360 degrees.

9. In a device of the character described, means for producing from a field frequency sawtooth signal a composite signal for field frequency shading of television pictures which comprises a parabola generator to which said sawtooth signal is applied and mixers for mixing the output from said parabola generator and said sawtooth signal for application to an iconoscope for shading purposes.

10. In a device of the character described, means for producing from a field frequency sawtooth signal a composite signal for field frequency shading of television pictures which comprises a parabola generator to which said sawtooth signal is applied and mixers for mixing the output from said parabola generator and said sawtooth signal and a sine wave from a power line for application to an iconoscope for shading purposes.
